UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

TELEPHONE PAY-STATION.

No. 872,628.

Specification of Letters Patent.

Patented Dec. 3, 1907.

Application filed November 16, 1905. Serial No. 287,606.

To all whom it may concern:

Be it known that I, GEORGE A. LONG, citizen of United States of America, residing at Hartford, in the county of Hartford and 5 State of Connecticut, have invented certain new and useful Improvements in Telephone Pay-Stations, of which the following is a specification.

My invention relates to devices for collecting a toll for the use of a telephone instrument and it is particularly adapted for use in connection with telephones of the automatic type in which there is no central operator to make the connections, but in which 10 the subscriber manipulates the apparatus to put his instrument in circuit with the one which he desires to call, and then presses a button which rings the bells at the called station. The general mode of operation of 15 these machines is well understood and my invention relates in no way to this part of the apparatus, it being confined entirely to the devices by which a toll may be collected.

The particular object of the invention is to 20 provide means whereby the calling subscriber need not pay for the use of the instrument unless he gets into communication with the station which he is calling to the extent of being able to hear, but unable to converse. In accomplishing this object the receiver of the telephone is in a normally closed circuit and the transmitter is in a normally open circuit, the transmitter circuit being closed by the deposited coin.

35 In the drawings Figure 1 is a general view of a telephone set of the automatic type with my invention applied thereto. Fig. 2 is a detail perspective view of the mechanism of my pay station with the casing removed to 40 clearly show the construction. Fig. 3 is a perspective view of a pay station showing the coin slot open. Fig. 4 is a similar view to Fig. 3 but showing the coin slot closed as by the switch hook lever with the receiver 45 hung on it. Fig. 5 shows diagrammatically one way in which the transmitter circuit is closed.

Referring to the drawings *a* denotes in general the case for the telephone instrument, *b* 50 the transmitter, *c* the receiver on the switch hook lever *d*, *e* the connection dial, *f* the ringing push button, and *g* denotes in general the pay station.

I will now describe in detail the mode of 55 operation of this telephone system. It is

well understood that the receiver is first removed from the hook, which action unlocks the connection dial and the desired connection is made by manipulating the dial in the usual manner. Placing the receiver to the 60 ear, the button *f* is pressed; the calling subscriber can immediately tell if the line is busy by a peculiar noise which he will hear. If the line is free the bells at the called station will be rung.

65 Pay stations have been applied to instruments of the automatic system before but have been operated in such a manner that it was necessary for the calling subscriber to deposit the coin before the push button 70 would become operative to ring the bells at the station desired. In consequence, if there was no answer from the called station the calling subscriber would lose his money without getting any service in return. By 75 my present invention this objection is removed.

Referring to Fig. 5 it is seen that the branch 1 of the transmitter circuit is closed while the branch 2 is broken, one end being 80 connected with the binding post 3 and the other with the binding post 4, the blocks 5 6 on which these binding posts are mounted being insulated from one another. From the binding post 4 this branch of the transmitter 85 circuit goes to the battery and then out onto the line. The coin or token which is to pay for the service is dropped through a suitable coin channel and deposited between the insulated blocks 5 6, bridging the gap in the 90 branch 2 of the transmitter and putting it in circuit so that the calling subscriber can talk to and be heard by the called party. It will thus be seen that the entire mechanism is always operative with the exception of the 95 transmitter, permitting the calling subscriber to know whether or not anyone answers at the called station; if he gets the answer at the receiver then he deposits his coin, putting the two instruments into full communication.

In carrying out my invention I have devised certain novel features of construction which I will now proceed to describe.

The mechanism comprising my pay station is inclosed in the upper part *g'* of the casing *g*, the lower part *g''* being the money compartment. Referring more particularly to Fig. 2, 7 is the coin slot and 8 the coin channel leading down to a position to dis- 110

charge the coin between the blocks 5 6. 9 is a return channel into which false and small coins are dropped and delivered at the outside of the case into the clip g^3 . The blocks 5 6 are separated some little distance from one another; on the block 5 is mounted a downwardly extending lever 10 upon which a slight pressure is exerted by the spring 10^a tending to throw it toward the block 6, forming a tapering recess of slightly less width than the diameter of the coin. From the side of the block 5 a plate 11 projects towards the block 6 against which the side of the coin rests. A lever 12 extends through the front door of the telephone casing and has at its inner end the rod 13, whose upper end is arranged in operative relation with the switch hook lever, as clearly shown in Figs. 3 and 4. This lever 12 has two arms, one 14 projecting upwardly and carrying at its end a plate 15 adapted to fit over and close the coin slot 7. The lower branch of the lever 16 has at bottom a stop 17 which is projected over the coin depositing outlet 18 when the receiver 20 is off the switch hook to hold the coin in place to form the connection between the ends of the branch 2 of the transmitter circuit. This lever 12 takes the position in Figs. 2 and 3 when the receiver is off the switch hook lever, as clearly shown. When the receiver is placed on the switch hook lever its weight drops the lever down to the position shown in Fig. 4 which throws the plate 15 over to close the coin slot 7 and draws the stop 17 out from under the coin allowing it to drop through the depositing outlet 18 into the money box.

The operation of the device is as follows. The calling subscriber removes the receiver 40 from the hook, manipulates the connection dial and rings the bells by pressing the button f . The action of removing the receiver from the switch hook lever allows the rod 13 to rise under the impulse of the spring 13^a, 45 rocking the lever 12 to uncover the coin slot 7 and throw the stop 17 into the path of movement of the coin. If the called party responds the coin is deposited through the coin slot 7 passing down through the coin channel 50 8, dropping into the position shown in Fig. 2 between the block 6 and the lever 10 and resting on the stop 17. The coin is tilted slightly in this position so that it rests with its side against the plate 11. It will also be 55 seen that it is wedged in between the block 6 and the lever 10, which, being spring mounted, yields slightly; thus a contact is provided not only on the edges but on the side of the coin. This completes the transmitter circuit 60 and throws the two instruments into full connection so that the calling subscriber can talk to the party at the called station. When the conversation is ended the receiver is hung up on the switch hook lever drawing 65 it down to the position shown in Fig. 4 which

through the rod 13 rocks the lever 12 so that the plate 15 closes the coin slot and the stop 17 is withdrawn from under the coin. This lower branch 16 of the lever carries a pin 19 which rides up the upwardly inclined projection 20 on the lever 10, throwing the lever 10 back away from the block 6, allowing the coin to pass through the depositing outlet 18 into the money box. The plate 15 acts as a guide to prevent a person from dropping in a coin before the receiver is removed from the switch hook lever in which case the coin would fall entirely through the device into the money box without giving the user any return.

80 I claim as my invention:

1. In a telephone pay station device for use in connection with an automatic telephone system in which the receiver is normally in a closed circuit and the transmitter 85 normally in an open circuit, comprising fixed blocks connected with the ends of the broken branch of the transmitter circuit, said blocks being insulated from one another, a coin channel having its outlet arranged so as to 90 deliver a coin between said blocks to complete the circuit, and means controlled by the switch hook lever for holding said coin in position between said blocks while the receiver is off the hook.

95 2. A telephone pay station for use in automatic telephone systems in which the receiver circuit is normally closed and the transmitter circuit normally open, comprising the casing having a coin slot, a coin channel within the casing registering with said slot, two fixed blocks insulated from one another and connected with the ends of the broken branch of the transmitter circuit, said coin channel being arranged to deposit the 100 coin between said blocks to close the circuit, and a stop having operative connection with the switch hook lever and adapted to hold said coin in position between said blocks when the said lever is raised and to be withdrawn from under the coin when said lever is depressed by the weight of the receiver.

105 3. A telephone pay station adapted for use with an automatic telephone system in which the receiving circuit is normally closed and the transmitter circuit normally open, comprising the casing having a coin slot, a coin channel within the casing registering with said coin slot, fixed blocks insulated from one another and having the ends 110 of the broken branch of the transmitter circuit secured thereto, the delivery end of said coin channel being arranged above the space between said blocks in order to deposit a coin to close the gap in the transmitter circuit, 115 and mechanism independent of said blocks and having operative connection with the switch hook lever by which the coin slot is closed and the coin deposit outlet opened when the lever is down, and the coin slot 120 125 130

opened and the coin deposit outlet closed when the lever is raised, all substantially as described and for the purposes set forth.

4. In a telephone pay station device in which there is a normally open circuit adapted to be closed by the coin which is deposited in payment for the use of the circuit, fixed blocks insulated from one another and connected with the ends of the broken circuit wires, a pivoted lever mounted on one block and projecting downwardly and towards the other block, said lever when in position to receive a coin forming with the opposite block a tapering recess, substantially as described.

5. In a telephone pay station device in which there is a normally open circuit adapted to be closed by the coin which is deposited in payment for the use of the instrument, fixed blocks insulated from one another and connected with the ends of the broken circuit wires, a lever pivoted to one block and projecting downwardly and towards the other block, a spring tending to throw the lower end of said lever towards the opposite block to form a tapering recess to receive the coin, means connected with the switch hook to retract said lever when said hook is down.

6. In a telephone pay station device in which there is a normally open circuit adapted to be closed by the coin which is deposited in payment for the use of the instrument, fixed blocks insulated from one another and connected with the ends of the broken branch of the transmitter circuit, a lever pivotally mounted on one of the blocks extending downwardly and spring pressed toward the opposite block to form a tapering recess into which the coin is deposited edge-wise, and a plate mounted on said block and forming a support against which the side of the coin lies, a coin channel arranged to deposit a coin to close the circuit between said insulated blocks, the switch hook, and mechanism connected therewith for holding

said coin between said blocks while said hook is raised, said mechanism being withdrawn when said hook is down and retracting said lever to allow the coin to pass to the money box.

50

7. A telephone toll apparatus for use in connection with automatic telephone systems in which the receiver circuit is normally closed and the transmitter circuit normally open comprising a casing inclosing the toll collecting mechanism and a money box, a coin slot through the top of said casing, a coin channel registering with said coin slot, a coin depositing outlet through the top of said coin box, said coin channel registering with but terminating at a distance above said coin depositing outlet, fixed blocks insulated from one another, each being connected with one end of the broken branch of the transmitter circuit, said blocks being located at either side of said coin depositing outlet, a lever pivotally mounted on one block extending downwardly between said blocks and spring pressed towards the opposite block, a switch hook, a stop lever having operative connection therewith and carrying at its lower end a stop projection adapted in connection with said lever and the opposing block to form a pocket to receive and hold the deposited coin when the receiver is off, the switch hook, and engaging parts on said stop lever and said spring pressed lever whereby when the receiver is on the switch hook and the stop lever withdrawn said spring pressed lever is retracted to permit the coin to pass through the coin deposit outlet into said box, substantially as described.

In testimony whereof I affix my signature in presence of two witnesses.
